UNITED STATES PATENT OFFICE.

ALFRED MONARD, OF PARIS, FRANCE.

APPARATUS FOR CONTROLLING RAILWAY-POINTS.

1,322,929.

Specification of Letters Patent. Patented Nov. 25, 1919.

Application filed October 24, 1918. Serial No. 259,562.

To all whom it may concern:

Be it known that I, ALFRED MONARD, a citizen of the Republic of France, residing at 66 Rue de la Chaussée d'Antin, Paris, France, have invented certain new and useful Improvements in Apparatus for Controlling Railway-Points, of which the following is a specification.

This invention relates to apparatus for 10 electrically controlling railway points from a distance designed to secure certainty of operation and a control visible in the pointsman's cabin.

The apparatus comprises essentially a 15 mechanism which operates in conjunction with two electric circuits, one being that of the electric motor, the other the control circuit. The electric motor is coupled to a worm which drives a worm wheel constituting the periphery of a nut which works on a screw; the latter being prevented from turning on its axis and being adapted to slide, is moved axially by the nut and transmits the movement to the points.

25 The screw which may be called the driving screw, is axially bored to receive the rod which is connected with the points and the engagement between the rod and the screw is a frictional one consisting of washers 30 threaded on the rod and held in the screw. Thus the rod can slide within the driving screw when subjected to a pressure exceeding a certain value depending upon the number of washers, the object being to prevent 35 damage to the mechanism in the event of an obstacle to the movement of the points, or of the points being moved by a passing train; should the normal relative position of the rod in the driving screw be disturbed 40 from any such cause it is re-established by the next operation of the points.

The accompanying drawings illustrate the invention, Figure 1 being a longitudinal section through the apparatus, Fig. 2 a horizontal section, Figs. 3, 4 and 5 cross sections on lines X—X, Y—Y, and Z—Z respectively of Fig. 2. Fig. 6 shows a detail of construction and Figs. 7, 8 and 9 are diagrams illustrating the electrical connections.

50 The mechanism is inclosed in a tight box 57 having a cover 58. The points rod 66 extends through the side of the box at right angles to the track and is engaged by the driving screw 64. The latter is moved axially by 55 rotation of the nut 63 which is also a worm wheel carried in ball bearings 150 and driven

by the worm 62 connected by a coupling 61 with the shaft of the electric motor 60. The motor is electrically connected with suitable contacts situated in the part of the box on 60 the opposite side of the driving screw.

For a portion of its length the driving screw 64 is bored to a diameter greater than that of rod 66 and the cavity thus formed is packed with a number of washers 65 65 threaded on the rod and exerting thereon sufficient friction to insure the movement of the points together with the driving screw under normal conditions. A gland 151^a keeps the washers in place and there is a like 70 gland 151^b at the other end of the driving screw.

When it arrives at each end of its stroke the driving screw 64 operates a lever 72 adapted to press a plunger 73 that operates 75 by means of a lever 69 the commutators of the several electric circuits. A shaft 68, to which this lever 69 is fixed, carries fixed to it two hammers 67^a, 67^b (Figs. 1 and 4) each terminated by a roller of insulating 80 material adapted to press against a contact spring 2 or 6. In the position of rest the lever 69 is held by one or other of the catches 70^a, 70^b which are pressed against the lever by springs 71.

When the driving screw 64 has moved to an extent necessary to bring the points to their new position, the corresponding lever 72, say the lower one in Fig. 2, is pressed by the end of the screw and pushes its plunger 73, thus compressing the spring 74^a contained in the latter. In the course of its stroke the plunger engages the catch 70^a and turns it to liberate the lever 69, thereupon the spring 74^a extends itself and turns the lever 69 through a small angle and with it the hammers 67^a and 67^b; thus with a sudden movement the hammer 67^a moves the contact spring 6 and interrupts the circuit completed thereby while the hammer 67^b moves 100 spring 2 against a contact, thereby preparing the closing of the circuit for the inverse direction of movement of the points.

At the same time that the foregoing invention is made there is closed a circuit in 105 which is the controlling device situated in the pointsman's cabin so that this device notifies the proper movement of the points. For this purpose the cranks 75, 76 are connected respectively with the point tongues. 110 They are keyed to shafts 77, 78, respectively carrying cams 79, 80 (Fig. 5), each cam hav-

ing a suitable notch. Thus the movement of the tongue of the point is translated into a rotation of the corresponding shaft 77 or 78. The shaft 68 carries free to turn on it 5 two levers 81^a, 81^b, each terminated by a roller of insulating material adapted to move contact springs 3 and 7 respectively.

Considering two of the cams situated in the same plane and assuming that one point 10 tongue is close to its rail and the other separated, as should be the normal position, these cams are in such angular position that projections 152 and 153 on the lever 81^a enter the notches in the cams so that the lever 15 turns on the shaft 68, permitting spring 7 to come against its contact and thus close the corresponding control circuit.

The points motor is connected with the 20 central apparatus in the cabin by a cable of four conductors which enters at the lower part of the box 57 (Fig. 6) and is kept in place by a flanged socket 82 forming a tight joint. The part of the cable that enters the 25 box is stripped as far as its lead sheathing and this latter is electrically connected by a cone of plastic conducting material pressed into the socket so as to perfect the joint against entrance of water and to make a satisfactory electrical connection between 30 the mass of the points motor and the sheathing which constitutes the return conductor to the cabin. The cable within the box enters a junction box 85 with terminals which cannot be disconnected.

35 The diagrams, Figs. 6, 7, 8 and 9, illustrate the operation, the position of the parts in Fig. 7 corresponding with the end position of the points when moved to the right. Fig. 8 shows the position of the parts at the beginning of the movement of the points in the opposite direction and Fig. 9 shows the position when the points are at the end of their movement in this direction.

It is assumed that the hammers 67^a and 45 67^b and the levers 81^a and 81^b are superposed in the diagrams. The switch or the like to be operated by the pointsman in his cabin is indicated at 154. It can be turned to establish connection between either of the 50 springs 1 and 5 and the positive pole of a source of current 155, the negative pole of which is earthed. The points motor 156 is brought either into circuit 157 or into circuit 158 by means of the springs 2 and 6 respectively. The control circuits 159 and 160 are brought into series with the motor circuits by springs 3 and 7 respectively so that current flows through one of them and the corresponding controlling apparatus, 4 or 8 as 55 the case may be, to earth.

In Fig. 7 the points motor having completed the movement of the points, the

spring 2 has been moved by hammer 67^b and spring 3 by the lever 81^b so that the control 65 circuit 160 is closed. At the same time lever 67^a has caused spring 6 to close the motor circuit 158 ready for the reverse movement of the points, which, however, does not occur until switch 154 has been turned to permit spring 5 to connect the circuit with the 70 source of current (Fig. 8).

When the points are again home, the hammer 67^a moves the spring 6 to interrupt the motor circuit and to cause it to complete the control circuit 159 in conjunction with 75 spring 7 which has been moved by lever 81^a (Fig. 9).

By again reversing the switch 154 the 80 points can be once again moved into the original position.

Having thus described the nature of the 85 said invention and the best means I know of carrying the same into practical effect, I claim:—

1. Apparatus for electrically operating 90 railway points comprising a driving screw adapted to slide without turning, a nut working on this screw and formed as a worm wheel and driven by a worm coupled to the shaft of the electric motor and a points 95 rod connected with the driving screw so as to be moved thereby.

2. In apparatus having features referred to in claim 1, the construction in which the driving screw is axially bored to receive the 100 points rod and contains a cavity to receive washers threaded on the rod and held in the cavity, the dimensions of the parts being such that the friction between the washers and the rod insure movement of the latter together with the screw so long as the power to be transmitted for moving the points is normal but to allow relative movement of the screw and rod when this power is exceeded or the points are forcibly moved. 105

3. In apparatus having the features referred to in claim 1, plungers adapted to be operated by the driving screw at each end of its stroke and thereby to liberate a lever to turn a shaft which determines interruption 110 of the existing motor circuit and the preparation of the circuit for the reverse movement of the points and at the same time closes a control circuit which includes a signal in the pointsman's cabin, the two shafts 115 which are thus turned by operation of the plungers being connected respectively with the point tongues through cranks and carrying cams which must be in a definite relative angular position in order that the operating levers may close the control circuit. 120

In witness whereof I have hereunto signed my name.

ALFRED MONARD.
